(57) **CLAIM**

The ornamental design for a dovetail retainer clip, as shown and described.

DESCRIPTION

FIG. 1 is a perspective view of a dovetail retainer clip, showing my new design;

FIG. 2 is a back perspective view of the dovetail retainer clip shown in FIG. 1;

FIG. 3 is a lower perspective view of the dovetail retainer clip shown in FIG. 1;

FIG. 4 is a lower back perspective view of the dovetail retainer clip shown in FIG. 1;

FIG. 5 is a left side elevation view of the dovetail retainer clip shown in FIG. 1;

FIG. 6 is a right side elevation view of the dovetail retainer clip shown in FIG. 1;

FIG. 7 is a back elevation view of the dovetail retainer clip shown in FIG. 1;

FIG. 8 is a front elevation view of the dovetail retainer clip shown in FIG. 1;

FIG. 9 is a bottom plan view of the dovetail retainer clip shown in FIG. 1;

FIG. 10 is a top plan view of the dovetail retainer clip shown in FIG. 1;

FIG. 11 is a perspective view of the dovetail retainer clip shown in FIG. 1 and engaged with a dovetail slot of a trim piece; and,

FIG. 12 is a perspective view of the dovetail retainer clip shown in FIG. 1 being used to attach a trim piece to a shelf. The details shown in broken lines are for illustrative purposes only and form no part of the claimed design.
